FACE PLATE FOR SPIROMETER MEDICAL APPARATUS

Bernard N. Gray, East Pepperell, and John W. Burke,
Melrose, Mass., assignors to Life Support Equipment
Corp., Burlington, Mass.

Filed Feb. 26, 1971, Ser. No. 119,443

Term of patent 14 years

Int. Cl. D24—01

U.S. Cl. D83—1

FIG. 1 is a perspective view of a face plate for a spirometer medical apparatus embodying our design;

FIG. 2 is a rear view of the face plate depicted in FIG. 1; and

FIG. 3 is a side view of the face plate for the spirometer medical apparatus shown in FIG. 1.

We claim:

The ornamental design for a face plate for spirometer medical apparatus, substantially as shown.
